Primary Examiner — Kendra Leslie Hamilton(74) *Attorney, Agent, or Firm* — Quantum Patent Law Firm(57) **CLAIM**

The ornamental design for a face-shaped teether, as shown and described.

DESCRIPTION

FIG. 1 is a front, left perspective view of a face-shaped teether, showing my new design;

FIG. 2 is a rear, right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the face-shaped teether that form no part of the claimed design.

1 Claim, 4 Drawing Sheets(56)
